UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed June 13, 1919, Serial No. 304,069. Renewed November 25, 1927.

My invention relates to mining apparatus. It has for its object to provide an improved mining apparatus especially adapted to room or entry work and having increased flexibility, whereby the same may be readily transported and when desired adapted to service under varying conditions. A further object of my invention is to provide an improved truck mounted kerf cutting apparatus having improved supporting, guiding and adjusting means, preferably normally forming a part of a compact truck mounted structure and adapted, while still supported by the truck, to insert a transverse kerf in a face across the front of the truck between points disposed laterally substantially beyond the lines of the truck. Further objects of my invention include the provision of improved means whereby the apparatus may be utilized to cut room necks or cross cuts or a kerf in an oblique face, or rooms or entries of varying width. These and other objects and advantages of my improved construction will, however, hereinafter more fully appear.

In the accompanying drawings I have shown for purposes of illustration one embodiment which my invention may assume in practice.

In these drawings,

Fig. 1 is a side elevation showing this form of my improvement in transport position on its truck.

Fig. 2 is a plan view of the construction shown in Fig. 1.

Fig. 3 is a diagrammatic plan view showing the apparatus in one of its intermediate positions preparatory to starting a kerf at the right rib.

Fig. 4 shows the apparatus in another intermediate position preparatory to starting a kerf at the left rib.

Fig. 5 is a similar view showing the apparatus making its sumping and transverse cuts at the right rib.

Fig. 6 is a similar view of the apparatus, showing the position of the parts during shifting of the guiding frame.

Fig. 7 is a similar view of the apparatus used in cutting a room neck or cross cut, the cutter bar being shown in a plurality of dotted line positions.

Fig. 8 is a diagrammatic view showing the apparatus in use on a diagonal face.

In this illustrative construction, I have

shown a machine of the general construction described and claimed in my co-pending application Serial No. 260,708, over which this application covers an improved adaptation. As the construction of the machine per se is described and claimed in that application and does not enter specifically into this invention, it will therefore here suffice to say that a machine frame 1 is provided, having thereon a rotatable element 2 and a rotatable element 3, adjustable one relative to the other, so that a cutter bar 4 carried by an enlarged front head 5, and itself carrying the usual cutter chain 6, may be adjusted into any desired plane relative to the face, and thereafter swung transversely in the desired plane through suitable power operated mechanism (not shown) carried within the front head 5 and controlled by suitable controlling means including a member 7.

In my improved construction it will be observed that the rear end of the frame 1 is provided with a feed driving member 8 driven from the machine in a usual manner and rotatable on a vertical axis, herein in the form of a usual chain driving sprocket, and provided with suitable cooperating guiding members 9 disposed on the front and rear ends of the frame and adapted to cooperate with a feed chain 10 in a well known manner. As shown, the frame 1 is disposed horizontally in and fixed to a swiveled frame 11, which is in turn swiveled at 12 and slidably supported in an elongated longitudinally disposed guiding frame 13. As shown, this frame 13 is itself also slidably mounted in a lower, herein shorter, frame 14, in turn swiveled at 15 on the wheeled truck frame 16 and with the swivel 15 slidably longitudinally of the latter frame. Thus it will be observed that a construction is provided which may be compactly assembled for transport in the normal longitudinally disposed transport position of the parts illustrated in Figs. 1 and 2 and which may be conveniently transported from place to place about the mine in a usual manner as by providing a suitable motor drive for the truck. Herein, for convenience this truck drive is illustrated, in the form of a separate truck driving motor 17 carried on the rear end of the frame 16 and operatively connected to the truck wheels 18.

When my improved apparatus with its

parts in transport position is brought into a room, a suitable support, herein in the form of a plurality of jacks 19, is set beneath the front end of the truck frame 16. Through 5 operatively connecting the chain 10 with one or the other of a plurality of hooks 20 on the opposite sides of the front end of the truck frame, it will be observed that the machine may then be fed forward with the frame 13 and frame 14 to a position on the front end of the truck frame 16 (Fig. 3). During this 10 movement, it will also be observed that through operation of the controlling member 7, the cutter bar 4 may be swung to the right or left, as shown in Figs. 3 or 4. After 15 this movement, the front end of the frame 13 is also preferably swung about its swivel, manually or, if desired, by suitably connecting the chain 10 to one of a pair of hooks 21 on the front end of the frame. In Fig. 3, wherein the cut is to be started at the right rib, it will be observed that the cutter bar is 20 swung to the left and the front end of the frame 13 is swung to the right until it occupies the transverse position indicated. In 25 this position of the frame 13, the right hand end of the same is then suitably fixed, as by jacks 22. Then, through connecting the end of the feed chain 10 with one of the hooks 21, the machine is fed from the position shown in Fig. 3 to the position shown in Fig. 5, with its bar preferably still disposed transversely. As soon as the machine frame is disposed in the position shown 30 at the right in Fig. 5, i. e. closely adjacent the right rib, through manipulation of the controlling member 7 the bar 4 is swung to the right from the transverse position illustrated to sump it under the coal, as also shown in Fig. 5. When the bar has thus been sumped in under the coal, it will be observed that by 35 again simply connecting the chain 10 to one of a plurality of hooks 23 provided at the opposite end of the frame 13 and, if necessary, placing suitable jacks 24 in position at that end of the frame, the machine may be started toward the left upon its transverse cut. When the machine, however, reaches a 40 position over the front end of the truck frame 16, the movement of the same is stopped and the jacks 22 and 23 at the opposite ends of the frame 13 are removed. Then, after a 45 suitable jack 25 is placed against the machine, as shown in Fig. 6, the feed chain 10 is connected to the hooks 21 on the right hand end of the frame 13 so that by the pull of the chain the frame 13 may be slid beneath the machine frame transversely from the 50 position shown in full lines in Fig. 6 to the position shown in dotted lines in that figure. Obviously, upon then removing the jack 25 and suitably setting the supporting jacks 22 and operating the mechanism as heretofore, the transverse cut may be completed by running the machine over into engagement with

the left rib. Then the bar may be removed from the cut and the mechanism assembled in transport position on the truck ready for transport to another place. In Fig. 4 it will be observed that I have illustrated an intermediate step in the disposition of the machine for starting a cut at the left hand rib. In this use of the apparatus, it will be observed that the machine is moved forward as in Fig. 3, but that, on the contrary, the bar 70 75 80 85 90 95 100 105 110 115 120 125 130 4 is swung to the right and the frame 13 is swung to the left. Obviously, with the parts in this position, through the connection of the mechanism as hereinabove described, the machine may be supported and moved laterally into sumping position at the left hand rib, sumped in under the coal, and then moved to the right to make a transverse cut toward the right rib with substantially the same operation in the same stages as described above in connection with the disclosures in Figs. 3, 5, and 6.

In Fig. 7 I have also illustrated the use of my improved apparatus in cutting room necks or cross cuts. In this use of the same, it will be observed that the frame 13 is simply swung about its swivel in such a manner as to bring the machine opposite the center line of the desired room neck or cross cut, the end of the frame 13 extending beyond the truck on either side desired. When the frame 13 is in this position, its front end is supported by the jacks 22 as hereinabove described. Then, through operation of the controlling member 7, the bar 4 is swung laterally to the sumping position shown in full lines, and through connecting the feed chain 10 with one of the hooks 21 on the front end of the frame 12, the machine is moved bodily forward in such a manner as to cause its bar to occupy the dotted line position A. From this position, through further operation of the controlling member 7, the bar is then swung laterally into the dotted line position B. The withdrawal cut, which results in the bar being brought to the dotted line position C, is then made by simply connecting the end of the feed chain 10 to one of the hooks 23 at the rear end of the frame 13, the rear end of the latter at that time preferably being fixed in position by the jacks 24.

In Fig. 8 I have also illustrated my improved mechanism as applied to use in cutting an oblique face. A cut of this type is desired under certain service conditions and is readily obtained in my improved construction wherein the frame 13 may obviously be readily swiveled into parallelism with any desired face, and the bar may be adjusted angularly relative to the frame, the ribs being kept straight by varying the angle of the bar. Here it will also be observed that since my improved construction is capable of being so disposed angularly, it is thereby adapted to use in rooms or entries of varying width, the

angle of the cut being varied as desired to accommodate the mechanism to any particular width.

In the use of my improvement, it will be observed that the machine is stably supported and guided during a cut, either transversely in advance of the truck or at the side thereof, and when the machine is disposed at a point laterally beyond the truck, thereby giving a greater range of guided movement. It will also be observed that the supporting mechanism provided, while thus adapted to support the machine, is also capable of being very compactly disposed during transport, i. e. within the lines of the truck. Here, attention is also directed to the fact that through the use of guiding and supporting frames 13 of varying length, the apparatus may be adapted to cut either rooms or entries, as desired, and that with a frame of a given width the width of the entry or room cut may be varied as desired by varying the angle of the frame 13 relative to a transverse line. These and other advantages of my improved construction will, however, be clearly apparent to those skilled in the art.

While I have in this application specifically described one embodiment which my invention may assume in practice, it is to be understood that this form is used for illustrative purposes and that the invention may be modified and embodied in various other forms without departing from its spirit or the scope of the appended claims.

What I claim as new and desire to secure by Letters Patent is:

1. In a mining apparatus, a truck, a horizontally extending guiding frame swiveled thereon and slideable with its swivel longitudinally thereon, and a mining machine having a pivoted cutter bar and slideable under its own power longitudinally along said guiding frame.

2. In a mining apparatus, a truck, a horizontally extending guiding frame swiveled thereon and slideable with its swivel longitudinally thereon, and a kerf cutting mechanism swiveled on said guiding frame and movable longitudinally therealong under its own power.

3. In a mining apparatus, a truck, a horizontally extending guiding frame swiveled thereon and movable with its swivel longitudinally thereon, and kerf cutting mechanism slideable longitudinally along said frame and including a pivoted cutter bar disposable at either side of the center line of said frame.

4. In a mining apparatus, a truck, a transversely disposable guiding frame swiveled thereon and of materially greater length than the width of said truck, kerf cutting mechanism movable along said frame and between the ends thereof including a universally swiveled bar movable to trace a complete cylinder, and means driven by said kerf cutting

mechanism for moving said mechanism relative to said guiding frame.

5. In a mining apparatus, a truck, a transversely disposable guiding frame swiveled thereon and of materially greater length than the width of said truck, kerf cutting mechanism movable along said frame between the ends thereof and including a universally swiveled bar movable by said mechanism to trace a complete cylinder, and means driven by said kerf cutting mechanism for moving said mechanism relative to said guiding frame.

6. In a mining apparatus, a truck, a transversely disposable guiding frame swiveled thereon and of substantially greater length than the width of said truck, kerf cutting mechanism movable on said frame including a universally swiveled swinging bar movable by said mechanism to trace a complete cylinder, and means driven by said kerf cutting mechanism for moving said mechanism relative to said guiding frame and moving the latter bodily relative to its pivot.

7. In a mining apparatus, a wheeled truck frame having a longitudinal guideway, a frame slidably mounted on said guideway, a support swiveled on said second frame and having a longitudinal guideway, a third frame slidably mounted on said support, and kerf cutting mechanism carried by said third frame and movable bodily therealong during horizontal kerf cutting.

8. In a mining apparatus, a wheeled truck frame having a longitudinal guideway, a frame slidably mounted on said guideway, a support swiveled on said second frame and having a longitudinal guideway, a third frame slidably mounted on said support, and kerf cutting mechanism carried by said third frame including a cutter bar swingable horizontally relative to said latter frame.

9. In a mining apparatus, a support having a guideway, a frame slidably mounted on said guideway, a swiveled support on said frame, a second frame slidably mounted on said swiveled support and having a guideway, a third frame slidably mounted on said second frame, a swiveled support on said third frame, a frame mounted on said last mentioned swiveled support, and kerf cutting mechanism carried by said last mentioned frame.

10. In a mining apparatus, a support having a guideway, a frame slidably mounted on said guideway, a swiveled support on said frame, a second frame slidably mounted on said swiveled support and having a guideway, a third frame slidably mounted on said second frame, a swiveled support on said third frame, a frame mounted on said last mentioned swiveled support, and kerf cutting mechanism carried by said last mentioned frame including a cutter bar swingable horizontally relative to said latter frame.

11. In a mining apparatus, a support having a guideway, a guide frame movable longitudinally relative to said guideway and swiveled thereon for horizontal swinging movement relative thereto, a second guide frame slidably mounted on said first guide frame, and kerf cutting mechanism carried by and adjustable bodily relative to said last mentioned guide frame. 70
12. In a mining apparatus, a support having a longitudinal guideway, a guide frame movable longitudinally relative to said guideway and swiveled thereon for horizontal swinging movement relative thereto, a second guide frame slidably mounted on said first guide frame, and kerf cutting mechanism carried by said last mentioned guide frame and movable longitudinally relative thereto during cutting. 75
13. In a mining apparatus, a support having a longitudinal guideway, a normally longitudinally disposed transversely disposable guiding frame slidably mounted on said guideway and of substantially greater length than the width of said support, and kerf cutting mechanism including a horizontally swingable cutter bar cutting along said frame between its ends and disposable on said frame when the latter is transversely disposed wholly outside the lateral edges of said support. 80
14. In a mining apparatus, a support having a longitudinal guideway, a normally longitudinally disposed transversely disposable guiding frame slidably mounted on said guideway and of substantially greater length than the width of said support, and kerf cutting mechanism including a horizontally swingable cutter bar movable longitudinally and angularly relative to said frame between its ends and disposable on said frame when the latter is transversely disposed outside the lateral edges of said support. 85
15. In a mining apparatus, a support having a guideway, a normally longitudinally disposed and transversely disposable machine guiding frame swiveled on said support and movable relative to said guideway longitudinally of the latter, and a kerf cutting mining machine reciprocable relative to said guiding frame and swiveled thereon for rotation about a vertical axis between the sides and ends of said frame. 90
16. In a mining apparatus, a wheeled truck having a longitudinal guideway, a normally longitudinally disposed and transversely disposable machine guiding frame swiveled on said truck and movable relative to said guideway longitudinally of the latter, and a kerf cutting mining machine reciprocable relative to said frame and swiveled thereon for rotation about a vertical axis between the sides and ends of said frame. 95
17. In a mining apparatus, a truck having a longitudinal guideway, a normally longitudinally disposed and transversely dispos- 100
- able guiding frame swiveled thereon and movable relative to said guideway longitudinally of the latter, and kerf cutting mechanism including a kerf cutting member swiveled on said frame on a vertical axis disposed between the sides and ends of said frame and reciprocable longitudinally relative to said frame while in a single plane. 105
18. In a mining apparatus, a truck having a longitudinal guideway, a normally longitudinally disposed and transversely disposable guiding frame swiveled on said truck and slideable relative to said guideway, and a kerf cutting bar swiveled on said frame on a vertical axis and slideable bodily relative thereto between positions wherein said axis lies inside the limits of said frame and wherein it is outside the limits of said frame. 110
19. In a mining apparatus, a truck having a longitudinal guideway, a horizontal normally longitudinally extending and transversely disposable guiding frame thereon of a length greater than the width of said truck and slideable relative to said guideway, and kerf cutting apparatus including a motor movable under its own power laterally along said frame during horizontal kerf cutting to a position outside the edge of said truck when said frame is transversely disposed. 115
20. In a mining apparatus, a truck having a longitudinal guideway, a normally longitudinally extending and transversely disposable guiding frame swiveled thereon and movable relative to said guideway longitudinally of the latter, and kerf cutting apparatus movable laterally on said frame longitudinally of the latter during horizontal kerf cutting and disposable transversely thereof in a position between the ends thereof and wholly outside the lateral edges of the truck. 120
21. In a mining apparatus, a truck having a longitudinal guideway, a normally longitudinally disposed guiding frame swiveled on a vertical axis for transverse disposition on said truck and movable relative to said guideway longitudinally of the latter, and kerf cutting mechanism movable bodily along said frame and swiveled thereon on a vertical axis disposed within the limits of said frame but outside the lateral edges of the truck. 125
22. In a mining apparatus, a truck having a longitudinal guideway, a guiding frame swiveled for transverse disposition thereon and normally disposed within the outlines thereof, said frame being slideable on said guideway, and a mining machine swiveled on a vertical axis on said guiding frame and normally disposed within the outlines thereof. 130
23. In a mining apparatus, a truck having a longitudinal guideway, a normally longitudinally disposed guiding frame movable relative to said guideway longitudinally of the latter and of substantially greater length than the width of said truck and disposable transversely of the latter, and kerf cutting appa- 135

ratus disposable transversely of said frame during horizontal kerf cutting and movable bodily longitudinally therealong between its ends, said frame and cutting apparatus being 5 longitudinally disposable relative to said truck during transport.

24. In a mining apparatus, a truck having a longitudinal guideway, a normally longitudinally disposed guiding frame movable 10 relative to said guideway longitudinally of the latter and disposable transversely thereof and of materially greater length than the width of said truck, and kerf cutting mechanism including a cutter bar and a horizontal 15 machine frame, the latter being disposable parallel with said frame or transversely thereof during horizontal kerf cutting and movable bodily relative thereto in either position.

20 25. In a mining apparatus, a truck having a longitudinal guideway, a normally longitudinally disposed guiding frame disposable transversely of said truck and providing a stationary guideway during cutting, said 25 frame being movable relative to said guideway along the latter, and kerf cutting mechanism including a horizontal machine frame swiveled on said frame and disposable parallel therewith or transversely thereof during 30 horizontal kerf cutting.

26. In a mining apparatus, a support having a longitudinal guideway, a normally longitudinally disposed guiding frame disposable transversely thereof and of materially 35 greater length than the width of said support, said frame being movable relative to said guideway along the latter, and kerf cutting mechanism including a horizontal machine frame swiveled on and slidable bodily 40 along said frame and disposable parallel thereto or transversely thereof during horizontal kerf cutting.

27. In a mining apparatus, a support having a longitudinal guideway, a normally longitudinally disposed guiding frame disposable transversely thereof and adapted to constitute a stationary guideway during cutting, said frame being translatively adjustable relative to said guideway, kerf cutting 50 mechanism on said frame movable bodily laterally longitudinally thereof during horizontal kerf cutting, and means for shifting said frame transversely relative to said support and said cutting mechanism when said frame is transversely disposed.

28. In a mining apparatus, a support having a longitudinal guideway, a normally longitudinally disposed guiding frame disposable transversely of said frame and movable bodily laterally longitudinally thereof during horizontal kerf cutting, and power operated 60 means for shifting said frame bodily trans-

versely relative to said support and said cutting mechanism when said frame is transversely disposed.

29. In a mining apparatus, a support, a guiding frame disposed transversely thereof, kerf cutting mechanism disposed transversely of said frame and movable therealong when so disposed, said kerf cutting mechanism including a horizontally swingable cutter bar, and means for shifting said frame bodily relative to said mechanism and support transversely of each of the same. 70

30. In a mining apparatus, a support, a normally longitudinally disposed guiding frame disposable transversely thereof, kerf cutting mechanism disposable transversely thereof and movable therealong when so disposed, said kerf cutting mechanism including a horizontally swingable cutter bar, and power operated means for successively moving 80 said mechanism and frame transversely of said support while the frame is transversely disposed.

31. In a mining apparatus, a support, a horizontally extending transversely disposed bodily laterally shiftable kerf cutter supporting guideway swiveled thereon upon a laterally bodily adjustable axis of swiveling, and a kerf cutter mounted on said guideway and including a horizontally swingable cutter bar. 90

32. In a mining apparatus, a support, a horizontally disposed transversely disposable bodily laterally shiftable supporting guideway swiveled thereon at a point adjacent one end of said support, said supporting guideway moving longitudinally when shifted laterally with respect to said support, and a kerf cutter mounted on said guideway and including a horizontally swingable cutter bar. 100

33. In a mining apparatus, a support, a transversely disposed bodily laterally shiftable supporting guideway swiveled thereon and movable with its swivel bodily longitudinally thereof, and a kerf cutter on said guideway including a horizontally swingable cutter bar. 110

34. In a mining apparatus, a support having a guideway, a kerf cutter, a normally longitudinally disposed transverse kerf cutter supporting frame adjustable bodily translatively on said guideway and of substantially greater length than the width of said support and along which said kerf cutter is slidable during transverse kerf cutting, 115 and means for moving said frame longitudinally beyond the side of said support.

35. In a mining apparatus, a support having a guideway, kerf cutting means including a swingable cutter bar, and means of 125 materially greater length than the width of said support adjustably mounted on said guideway for movement along the latter and normally disposed longitudinally of said support and relative to which said kerf cut- 130

ting means is slidable for supporting said cutting means in a longitudinally disposed position laterally outside the lines of said support.

36. In a mining apparatus, a support, kerf cutting means including a swingable cutter bar, means relative to which said kerf cutting means is bodily slidably normally disposed longitudinally of said support but disposable transversely for supporting said kerf cutting means when the latter is longitudinally disposed and laterally beyond the lines of said support, and power means for moving said supporting means bodily laterally relative to the support.

37. In a mining apparatus, a truck, a normally longitudinally disposed supporting frame disposed transversely thereof and shiftable bodily transversely thereof when so disposed, kerf cutting mechanism disposed longitudinally of said truck including a horizontally swingable cutter bar, and power means for moving said cutting mechanism along said frame during cutting.

38. In a mining apparatus, a truck having a guideway, a normally longitudinally disposed and transversely disposable guiding member swiveled thereon and of a materially greater length than the width of said truck, said guiding member being adjustable bodily translatively relative to said guideway, and a kerf cutter swiveled on a vertical axis on said guiding member and slidable relative thereto and having a forwardly extending cutter bar.

39. In a mining apparatus, a truck having a guideway, a normally longitudinally disposed and transversely disposable guiding means swiveled thereon and of a materially greater length than the width of said truck, said guiding means being adjustable longitudinally relative to said guideway, and a kerf cutting mechanism movable along said guiding means and having a pivoted cutter bar projecting beyond the side thereof.

40. In a mining apparatus, a truck having a guideway, a normally longitudinally disposed and transversely disposable guiding frame swiveled thereon and of materially greater length than the width of said frame, said guiding frame being adjustable bodily relative to said guideway, a kerf cutter swiveled on said frame and having a pivoted cutter bar, and means for moving said kerf cutter bodily longitudinally along said frame.

41. In a mining apparatus, a truck having a guideway, a normally longitudinally disposed and transversely disposable guiding frame swiveled thereon and of a length materially greater than the width of the truck, said guiding frame being slidably adjustable relative to said guideway, a kerf cutter swiveled on said frame on a vertical axis and having a forwardly extending cutter bar,

and means for moving said kerf cutter bodily 65 longitudinally along said frame.

42. In a mining apparatus, a truck having a guideway, a normally longitudinally disposed and transversely disposable frame swiveled thereon and of materially greater 70 length than the width of said truck, said frame being bodily slidably adjustable relative to said guideway, and a kerf cutter slideable along said frame between the ends thereof and having a cutter bar disposable parallel 75 or laterally at right angles thereto.

43. In a mining apparatus, a support having a guideway, a normally longitudinally disposed and transversely disposable guiding frame thereon of materially greater length 80 than the width of said support, said guiding frame being adjustable translatively horizontally relative to said guideway, and kerf cutting means movable bodily longitudinally therealong during cutting while said frame is 85 transversely disposed for inserting a continuous transverse kerf in the face in advance of said support and extending from a rib at one side of said support to a rib at the other side thereof.

44. In a mining apparatus, a truck having a guideway, a normally longitudinally disposed and transversely disposable guiding frame of materially greater length than the width of said truck, said guiding frame being 95 adjustable bodily horizontally relative to said guideway, and kerf cutting means movable bodily longitudinally therealong during cutting for inserting a straight ribbed transverse kerf in advance of said truck and extending from the center of the truck to a point 100 at one side of said truck.

45. In a mining apparatus, a truck, a normally longitudinally disposed and transversely disposable guiding frame shiftable bodily 105 transversely thereon when transversely disposed, and transversely disposed cutting means movable longitudinally along said guiding frame during horizontal kerf cutting in different positions thereof including a 110 swingable cutter bar.

46. In a mining apparatus, a truck having a guideway, a transversely disposed frame thereon adjustable translatively relative to said guideway and disposable parallel to an oblique face, and a kerf cutting mining machine disposed transversely of said frame and movable under its own power laterally along said frame during horizontal kerf cutting 115 while said frame is disposed parallel to the rib and extending substantially beyond the sides of the truck.

47. In a mining apparatus, a truck having a guideway, a normally longitudinally disposed transversely disposable guiding frame 125 on said truck and slidably relative to said guideway, kerf cutting mechanism disposed transversely of said frame on said frame and

movable laterally therealong during horizontal kerf cutting, and means for adjusting said frame transversely into engagement with either rib of a room or entry.

5. 48. In a mining apparatus, a truck having a guideway, a normally longitudinally extending transversely disposable guiding frame on said truck and slidable relative to said guideway, kerf cutting mechanism on said frame, and means for adjusting said frame to form a continuous transverse kerf cutter support across a face of greater length than said frame and relative to which said kerf cutting mechanism is laterally movable during horizontal kerf cutting.

49. In a mining apparatus, a truck having a guideway, a transversely disposed machine guiding frame on said truck and slidable relative to said guideway, kerf cutting mechanism disposed transversely thereon adapted to move laterally therealong during horizontal kerf cutting, and means driven by said mechanism for adjusting said frame bodily transversely into engagement with either rib of a room or entry.

50. In a mining apparatus, a truck having a longitudinal guideway, a normally longitudinally extending transversely disposable frame on said truck and slidable relative to said guideway, kerf cutting mechanism on said frame, and means driven by said mechanism for selectively adjusting said frame bodily or moving said mechanism as a whole relative thereto.

51. In a mining apparatus, a truck having a guideway, an adjustable frame swiveled on said truck and adjustable translatively relative to said guideway, kerf cutting mechanism swiveled on said frame, and means driven by said kerf cutting mechanism for selectively adjusting said frame or moving said mechanism as a whole relative thereto.

52. In a mining apparatus, a truck, an adjustable swiveled frame thereon of materially greater length than the width of the truck and constituting a stationary guideway during cutting, kerf cutting mechanism swiveled on said frame and including a swingable cutter bar, and means driven by said mechanism for selectively adjusting said frame on or bodily rectilinearly with its swivel.

53. In a mining apparatus, a truck, an adjustable swiveled frame thereon of materially

greater length than the width of the truck, kerf cutting mechanism swiveled on said frame and including a swingable cutter bar, and means driven by said mechanism for selectively adjusting said frame on or bodily rectilinearly with its swivel or moving said mechanism longitudinally along said frame.

54. In a mining apparatus, a truck having a longitudinal guideway, a normally longitudinally extending transversely disposable frame thereon of materially greater length than the width of said truck, said frame being slidable relative to said guideway, kerf cutting mechanism supported on said frame for movement longitudinally therealong including a motor and a pivoted cutter bar, and power operated means actuated by said motor for moving said bar bodily or about its pivot when disposed in advance of the side of said frame.

55. In a mining apparatus, a truck having a longitudinal guideway, a normally longitudinally extending transversely disposable guiding frame thereon of materially greater length than the width of said truck, said frame being slidable relative to said guideway, kerf cutting mechanism movable on said frame including a cutter bar disposable in different planes, and means for moving said bar relative to said frame and between the ends thereof when said bar is disposed in different planes.

56. In a mining apparatus, a wheeled truck frame having a guideway, a normally longitudinally disposed transversely disposable guiding frame swiveled thereon and movable bodily relative thereto, and a self-contained mining machine having pivoted kerf cutting mechanism, said machine being swiveled on said frame for rotation about a vertical axis.

57. In a mining apparatus, a wheeled truck having a longitudinal guideway, a swiveled support slidable relative to said guideway, a guiding frame on said swiveled support, a second guiding frame slidably mounted on said first guiding frame, a second swiveled support slidably mounted on said second guiding frame, and a self-contained mining machine mounted on said second swiveled support and including feeding and kerf cutting mechanisms.

In testimony whereof I affix my signature.
MORRIS P. HOLMES.
